COLLAPSIBLE AWNING

Jorge Teofilo Freeman, Buenos Aires, Argentina

Application February 13, 1945, Serial No. 577,647
In Argentina December 29, 1944

4 Claims. (Cl. 160—62)

1

The present invention refers to improvements in or relating to awnings and more particularly refers to a collapsible awning consisting of units made of rigid and weather-resisting material.

The awnings now in use in order to protect entrances, shop windows and other places are generally made of canvas or similar flexible material and, while they are more or less satisfactory in providing shelter from the sun and rain, they have the distinct disadvantage of suffering from the effects of atmospherical conditions. Thus, when exposed to rain or wind, they are soon torn or damaged, and under the influence of rain or sunshine, they discolor within a relative short period of time. In view of this, many shop keepers do not unfold the canvas awnings above their shop windows or entrances when there are adverse weather conditions, in order to avoid their deterioration which, of course, means that the awning is not used for the purpose for which it is really destined. On the other hand, in those cases in which the awning must necessarily be used, for instance, when the awning is used to protect tables and chairs placed on the pavement in front of a restaurant, the life of the canvas awning is very limited and it must be periodically replaced in order to conform to the minimum requirements of aspect and appearance.

The principal purpose of my invention consists in providing an awning which will not be damaged, discolored or otherwise deteriorated by the effects of weather conditions and which will preserve, for practically unlimited periods of time, its original aspect and physical properties even if it is used day and night and exposed to the varying conditions of weather or seasonal changes.

Another main purpose of my invention resides in providing a collapsible awning consisting of a number of units made of rigid and weather-resisting material.

A further object of my invention is to provide an awning that may be given any desired shape; that is, it may have plain surfaces or these may be channelled, grooved, corrugated etc., or for advertising purposes the awning may take the shape or form of a shoe, umbrella, cup-and-saucer, etc., thereby alluding to the nature of the shop with which it is associated. Also, if desired, the awning may have the shape of a tunnel or covered corridor in which case it may be used in front of church entrances, hotels or clubs, particularly for marriages or similar ceremonies.

A still further object of the present invention

2

is to provide an awning made of transparent or opaque material permitting the obtention of certain light effects within the space covered by the awning. This feature may be used for advertising purposes or, if the awning is associated with a shop window, the same enables a given light effect to be obtained upon the goods exhibited in the shop window. Thus, for instance, it is possible to form the awning from colored material which colors the rays of light passing through the same and thereby, when used above a shop window causes the entire shop window to be illuminated in the respective given color.

An additional important object of my invention resides in providing a collapsible awning comprising a number of interchangeable units. This feature enables the use of, say, opaque and heat-insulating material in order to give shelter from the sun, and the use of transparent material in the same awning on rainy or cloudy days.

In order to achieve these objects and others which will become apparent from the detailed description of the invention which will be given hereinafter, the awning of the present invention comprises a frame adapted to be supported on a suitable support element, for instance, the wall of a building, and a number of units movably arranged on said frame, each unit being provided with downwardly extending members adapted to slide on the frame and with relatively short projections for interconnecting any two adjacent units and limiting the relative movement between them.

According to another feature of the invention, each individual unit, except the lowermost unit is provided at one of its ends with downwardly extending members adapted to slide on rail-like members of the supporting frame, and with relatively short projections arranged at the opposite end and adapted to slide on the upper surface of the next adjacent unit, the lowermost unit provided at the two opposite ends with downwardly extending members adapted to slide on rail-like members of the frame.

Other features of my invention will become evident from the following detailed description thereof, in which reference will be made to the accompanying drawings which illustrate by way of example some preferred embodiments of the invention and in which:

Figure 1 is a perspective view of one of the units employed in the awning of the present invention;

Figure 2 is a similar view of another unit which

is also employed in the awning of the present invention;

Figure 3 is a horizontal projection of several of the units when joined together;

Figure 4 is a section on line A—A of Figure 3;

Figure 5 is a perspective view of a unit according to another embodiment of the invention;

Figure 6 is a front elevation of one of the units mounted on the supporting frame;

Figure 7 is a sectional view of the same unit, 10 the section being taken on line B—B of Fig. 6;

Figure 8 is a side elevation of the awning including the frame, the same being shown in the position in which it is used;

Figure 9 is a similar view showing the awning 15 and frame in folded state;

Figure 10 is a front view of the awning showing some further structural details;

Figure 11 shows a side elevation of the awning comprising a rigid frame; and 20

Figures 12, 13 and 14 show several forms or shapes of the awning according to the present invention.

The same reference numerals have been used throughout the several figures in order to designate equal or equivalent parts of the device.

Referring first to Figures 8 and 9, it will be seen that the awning is secured to the wall *b* of a building, in which a cavity 15 has been made, this cavity having such shape and size that the awning may be kept therein in folded state. At the lower end of the cavity 15, two or more rail like members 11 are pivotally fixed to the wall *b* at 14. These members 11 are connected together by means of a transversal bar 13 (Fig. 10), the rails 11 and the transversal bar 13 thus forming a supporting frame capable of effecting a pivotal movement about the pins of pivots 14. In the position shown in Figure 1, the supporting frame is inclined, that is, the transversal bar 13 is in a horizontal plane below the plane in which the pivotal supports 14 are situated; preferably the transversal bar 13, should be provided with an upwardly extending flange forming an abutment as best shown in Figure 8 of the drawings.

The frame may be further supported, if desired, by the auxiliary supporting bars shown in Figure 8. Further, above the cavity 15 there may be provided a cover 19, pivotally connected to wall *b* at 20.

The frame carries a plurality of individual units 1 and 1a adapted to effect a sliding movement on the rails 11 in the longitudinal direction thereof. As shown in Figure 8, the units constitute a step-wise arrangement, the front units being lower in height than those which are nearer to the wall *b*, and the height of the units gradually increases up to that of the uppermost unit 1. This latter unit has been illustrated in detail in Figures 1, 6 and 7.

With reference to Figure 1, the unit 1 consists of a sheet or slab of rectangular shape provided at one of its edges with two downwardly extending members 2 and at the opposite edge with three downwardly extending projections 3. The sheet may be made of any suitable material, preferably of plastic material having good weather-resisting properties, and if desired, being colored and transparent. The projections 3 and also the downwardly extending members 2 may be integral with the sheet, and the preferred method of manufacturing them is by molding. However in some cases it may be advisable to have removable downwardly extending members 75

2 which may be fixed to the body of the unit by means of screws. In this case the downwardly extending members may be made of metal.

The remaining units 1a as shown in Figure 2 are substantially similar to units 1, but apart from downwardly extending members 2a and downwardly extending projections 3a, they have on their upper positioned surface three upwardly extending projections or butts 4, which are positioned exactly opposite the projections 3a. The position of the projections 3a and downwardly extending members 2a on the units 1a coincide with the position of projections 3 and members 2, respectively on unit 1, but on the other hand, the downwardly extending members 2a are shorter than members 2, the difference in height being somewhat greater than the thickness of the body of the units.

As shown in Figures 3 and 4, the units are resting on the supporting frame in overlapping relation and thus constitute a stepwise arrangement. The uppermost unit rests by means of its projections 3 on the upper surface on the adjacent unit 1a and, as they engage when the awning is opened, butts 4 of the adjacent unit 1a, both units are loosely joined together, the projections 3 and butts 4 having the effect of hooks which will limit the relative movement between the units in opposite directions. The remaining units are in the same manner loosely joined together with the lower next unit, respectively.

The downwardly extending members 2 and 2a are provided with rollers or wheels 8 (Figures 6 and 7) adapted to run on the rail-like members 11 of the frame. The wheels 8 are mounted on suitable bearings 9 which, for a purpose which will be explained later, have openings 21 adjacent their lower ends.

The lowermost unit 1a has at its lower end projections 3a provided with similar bearings and with rollers or wheels adapted to run on rails 11.

Some parts of the mechanism for operating the device have been represented in Figure 8 of the drawings according to which said mechanism may comprise a flexible cable 22 passing over a drum 23 mounted in a small cavity or chamber 24 made in the wall *b*. One end of the cable is secured to the drum 23 which may be driven in both directions by any suitable mechanism (not shown). The other end, after having been passed through the openings 21 of bearing members 9, is secured to the downwardly extending member 2a of the lowermost unit. A similar arrangement may be made at the opposite lateral end of the device so that there be two cables and two drums which latter should preferably be interconnected by a shaft 25 or the like in order to be rotated with the same speed. Also if desired, one cable and drum may be used in the central part of the units in which case a suitable downwardly extending projection should be provided at least on the lowermost unit 1a to which the cable would be secured.

If desired, the cable 22 may be used in order to lift the entire frame from the position shown in Figure 8 until it assumes the position illustrated in Figure 9, that is, in order to cause the frame to swing about the pin of pivot 14 in a counter-clockwise direction. In such case, it may be desirable to maintain the entire assembly when it assumes the position shown in Figure 9, slightly outwardly inclined so that, if the frame 70 is to be lowered, it will start moving due to its

own weight as soon as the drum 23 is released. Generally however, I prefer a separate mechanism (not shown) for lifting and lowering the frame consisting of rails 11 and transversal member 13, which may be any of the mechanisms known for this purpose.

The foregoing will sufficiently explain the simple operation of the device. In order to close the awning, the drum 23 is driven in a counter-clockwise direction so that the lowermost unit will move towards the adjacent unit 1a. As soon as its downwardly extending member 2a engages that of the next adjacent unit it will push the latter in the same direction and this effect will be again produced as soon as the downwardly extending member 2a of the second unit engages that of the third one, and so on until all units 1a have reached the space beneath the uppermost unit 1. Once the units are in this position, the frame may be lifted and the entire device will enter into the cavity 15, the rails 11 being kept in channels or grooves 16 provided for this purpose in the wall b. In order to lower the awning, the drum will be driven in clockwise direction and the results will be inverted.

In Figure 5, I have shown another embodiment of the units used in accordance with my invention. Instead of the units shown in Figures 1 and 2, I may use a frame-like structure 6, adapted to receive slabs or sheets of plastic or any other suitable material. The frame 6 is provided with downwardly extending members 2 and at the opposite end with downwardly extending projections 3, and on the upper surface, above the downwardly extending members 2, it has upwardly extending projections or butts 4, adapted to engage when the awning is unfolded, the projections 3 of the upper next frame-like structure 6. If the awning is of considerable width, it may be advisable to reenforce the structure 6 by transversal strips 7 as shown in Figure 5, or to make the slabs or sheets of a smaller width than that of the awning, and in this case, the frame-like structure 6 should have two or more sub-divisions. If desired clamping means or the like may be provided to retain the slab or sheet within the frame, or if same comprises several sub-divisions, within the respective sub-divisions. The frame-like structure 6 permits interchangeable slabs or sheets to be employed.

The assembly of the frame-like structures 6 is identical with the above described arrangement of the units shown in Figures 1 and 2, and it will be evident that the only change involved is that the slabs are not directly supported from the frame 11, 13 but are carried by the frame-like structures 6 which in turn are slidably supported from the frame 11, 13 by means of the rails 11 and rollers or wheels 8 already described. If I use the structure shown in Figure 5, I prefer to have the walls of the partitions or sub-divisions flush with the slabs or sheets carried by the structure, but, if desired, the longitudinal walls of the partitions may be somewhat lower than the surfaces of the slabs, so that they constitute grooves or channels through which the water may run down if the device is used in the rain, and water collecting means may be arranged at the lower end of the grooves. Also, if desired, the frame-like structure 6 may comprise, for instance, two partitions, the separating wall between these being somewhat higher than the walls at the lateral ends thereof, so that the slabs will be downwardly inclined towards the lateral sides of the awning and form a structure similar to the roof of a

gable. In this case the water will run towards the lateral sides of the awnings where suitable collecting means may be provided.

Figure 11 shows another embodiment of my invention. In this case the rails 11, instead of being pivotally attached to the wall b, are rigidly secured thereto, and, if desired, they may rest with their opposite ends on columns 18. Above the frame, at a height somewhat above the uppermost unit 2, a cover plate 17 is arranged and the units may be kept, when the awning is closed, in the space existing between the cover plate 17 and rails 11. In order to reduce in this position the size of the rails 11, they may be provided at one or more points intermediate their ends with pivotal articulations or hinges 14 permitting the rails to be folded up. These hinges may permit swinging movement around horizontal axes (that is, the corresponding parts of the rails are swung upwardly or downwardly) or around vertical axis, (that is, the rails may be collapsed by movement in the directions indicated by the arrows in Figure 10).

Figures 12, 13 and 14 illustrate some shapes 25 which the awning according to the present invention, may be given for advertising or other purposes. The hook-like joints constituted by the overlapping projections 3, 3a and 4, respectively, are situated at convenient places according to 30 the requirements of aspect or appearance and depending on the space available due to the particular shape adopted in a given case.

It will be understood that the drawings represent only some examples of several embodiments 35 of the invention and the latter is not limited to what I have shown and described. Thus for instance while I have shown inclined frames 11, 13, these may be arranged to be in a substantially horizontal plane. In this event, the operating 40 means should permit the units 1, 1a or 6 to be driven in both directions which may be achieved for instance, by an endless cable. Further in some cases, it may be desired to have the units 1, 1a, or 6, movable in a direction parallel to the wall b to which frame is attached. In this case, the rails 11 are of course arranged parallel to the wall b and the projections and downwardly extending members are to be disposed accordingly. This arrangement may be convenient for instance, where the awning is to be used above the 45 entrance of a shop and two shop windows arranged symmetrically at the sides of the entrance. In this case, I may mount two supporting frames which are downwardly inclined into opposite lateral directions from the space above the entrance, and the units adapted to be moved laterally from the space above the entrance towards the ends of the two shop windows respectively and vice-versa. In other cases, where the 50 space to be covered by the awning is much larger than usual, for instance in front of restaurants, the weight of the entire structure may be such, that there will be considerable friction when the projections 3, 3a travel during the sliding movement of the units along the upper surface of the slabs or sheets of the units. To decrease the friction, rollers or wheels may be provided at the lower ends of the projections 3 and 3a, associated 55 if desired, with runways disposed on the upper surfaces of the slabs or sheets. With reference to the embodiment of Figure 5, I already pointed out that this arrangement permits the use of interchangeable slabs or sheets. In order to make the units 1 and 1a of Figures 1 and 2 interchangeable, they may be provided (as already 60 70 75

pointed out above) with removable downwardly extending members 2, 2a so that one of the units 1a may be made the uppermost unit 1 and the order of the remaining units may be changed. This interchange may be desirable when colored slabs or sheets are used. Obviously, such removable downwardly extending members 2, 2a may also be used in conjunction with the frame-like structure 6 of Figure 5 or in conjunction with any of the other forms or shapes of units that may be used according to the invention. A further modification of my invention consists in arranging more than one of the units (for instance, those shown in Figure 3) in transversal rows one besides the other. In that case, the number of rails 11 must of course be one short of the number of units forming one transversal row. In these cases I prefer the intermediate rails 11 to have channel or U-shape the base of which is to be sufficiently wide as to receive the wheels of the two downwardly extending members 2, 2a which are laterally adjacent in this arrangement. These U-shaped rails, if inclined, may at the same time serve as paths for the water when the awning is used in the rain.

Further, as the uppermost unit remains stationary during the operations of opening and closing the awning, it may be secured to the wall or other support in conjunction with which the awning is used. In this case the uppermost unit 1, 6 may be provided with upwardly extending projections 4 engaging a corresponding downwardly extending member or members fixed, for instance, to the cover plate 17 or 19. By this arrangement the cable 22 or other operating means is relieved of the function of retaining the units in their respective places when the awning is open since the hook-like projections 3, 3a and 4 will take charge of this work.

It will be evident that any suitable illumination means may be used in connection with the awning. Thus, for example, two slabs or sheets of transparent clear or colored material may be arranged one above the other within the frame-like structure 6 and bulbs together with the necessary wires and electrical connections may be placed within the space between the two slabs or sheets.

If desired, the lower ends of rails 11 may be provided with doors or other suitable locking means which may be opened or unlocked when one or more of the units are desired to be removed from the supporting frame 11, 13.

These and other modifications are intended to be included in the scope of the invention as defined in the annexed claims.

Having now particularly described and ascertained the nature of my invention and in what manner the same is to be performed, I declare that what I claim is:

1. A collapsible awning comprising a supporting frame; two rail members forming part of said supporting frame; and a plurality of removable awning units each comprising a flat substantially sheet shaped awning member of rigid material, at least two supporting members extending downwardly from the lower surface of said awning member and adapted to engage and to slide upon said rail members of said supporting frame; at least one connecting projection extending downwardly from the lower surface of said awning member and adapted to freely slide on the upper surface of an adjacent awning member, and at least one connecting projection extending upwardly from the upper surface of said awning member and adapted to freely slide on the lower surface of an adjacent awning member and to engage said downwardly extending connecting projection on the same.

surface of an adjacent awning member and to engage said downwardly extending connecting projection on the same.

2. A collapsible awning comprising a supporting frame; two rail members forming part of said supporting frame; and a plurality of removable awning units each comprising a flat substantially sheet shaped awning member of rigid material, at least two supporting members extending downwardly from one edge of said awning member and adapted to engage and slide on said rail members of said supporting frame, at least one connecting projection extending downwardly from the opposite edge of said awning member and adapted to freely slide on the upper surface of an adjacent awning member, and at least one connecting projection extending upwardly from the same edge of said awning member as said downwardly extending supporting members and adapted to freely slide on the lower surface of an adjacent awning member so as to engage said downwardly extending connecting projection on the same.

3. A collapsible awning comprising a supporting frame; two rail members forming part of said supporting frame; and a plurality of removable awning units each comprising an awning frame, at least one awning sheet of rigid material removably supported by said awning frame, at least two supporting members extending downwardly from one edge of said awning frame and adapted to engage and slide upon said rail members of said supporting frame, at least one connecting projection extending downwardly from the opposite edge of said awning frame adapted to freely slide on the upper surface of an adjacent awning frame, and at least one connecting projection extending upwardly from the same edge of said awning frame as said downwardly extending supporting members and adapted to freely slide on the lower surface of an adjacent awning frame so as to engage said downwardly extending connecting projection on the same.

4. A collapsible awning comprising a supporting frame; two rail members forming part of said supporting frame; and a plurality of removable awning units each comprising an awning frame; at least one awning sheet of rigid material removably supported by said awning frame, at least two supporting members extending downwardly from one edge of said awning frame and adapted to engage and slide upon said rail members of said supporting frame, at least one connecting projection extending downwardly from the opposite edge of said awning frame adapted to freely slide on the upper surface of an adjacent awning frame, and at least one connecting projection extending upwardly from the same edge of said awning frame as said downwardly extending supporting members and adapted to freely slide on the lower surface of an adjacent awning frame so as to engage said downwardly extending connecting projection on the same.

5. A collapsible awning comprising a supporting frame; two rail members forming part of said supporting frame; and a plurality of removable awning units each comprising an awning frame; at least one awning sheet of rigid material removably supported by said awning frame, at least two supporting members extending downwardly from the lower surface of said awning frame and adapted to engage and slide on said rail members of said supporting frames, at least one connecting projection extending downwardly from said lower surface of said awning frame spaced from said downwardly extending supporting members and adapted to freely slide on the upper surface of an adjacent awning frame, and at least one connecting projection extending upwardly from the upper surface of said awning frame opposite said downwardly extending supporting members adapted to freely slide on the lower surface of an adjacent awning frame engaging said downwardly extending connecting projection on the same.
